Primary Examiner — Rebecca Tsehay(57) **CLAIM**

The ornamental design for an electronic heating rod as shown and described.

DESCRIPTION

FIG. 1 is a perspective view of an electronic heating rod showing my new design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is an enlarged view of area 9 circumscribed in FIG. 1; and,

FIG. 10 is an enlarged view of area 10 circumscribed in FIG. 2.

The broken lines consisting of evenly spaced dash lines in the drawings depict portions of the electronic heating rod that form no part of the claimed design.

The broken lines consisting of short and long dash lines encircling the enlarged detail views are for annotative purposes that form no part of the claimed design.
